UNITED STATES PATENT OFFICE.

ERNEST WENIGMANN, OF NEW YORK, N. Y.

CHAMBER-VESSEL.

SPECIFICATION forming part of Letters Patent No. 474,617, dated May 10, 1892.

Application filed February 5, 1892. Serial No. 420,467. (No model.)

To all whom it may concern:

Be it known that I, ERNEST WENIGMANN, of New York city, New York, have invented an Improved Chamber-Vessel, of which the following is a specification.

This invention relates to a chamber-vessel provided with several improvements; and it consists in the various features of construction more fully pointed out in the claims.

5 In the accompanying drawings, Figure 1 is a vertical central section of the vessel; Fig. 2, a top view of the same; Fig. 3, an end view of the seat and cover, and Fig. 4 a bottom view thereof.

10 The letter *a* represents the body of a chamber-vessel, which I make of oval form, in lieu of the usual circular form, in horizontal section—that is to say, the vessel is of elongated shape, rounded at one end *a'*, and tapering 15 toward the other end *a''*. The object of this form is to make the vessel more convenient for use by gentlemen.

Upon the rim *a* of the vessel *a*, I place a curved seat *b*, made in the form of a horseshoe, and which extends over the rounded 20 half of the vessel. The seat may be covered

by a suitable textile material, and it is secured to the rim *a* by means of a set of spring-jaws *b'*, that embrace such rim. To the seat *b* there is hinged a cover *c*, which is of a size 30 to close over the entire vessel. This cover is provided with a thickened-end section *c'*, Fig. 3, which permits the cover to reach down upon the rim *a*, where the latter is not covered by the seat. Thus it will be seen that 35 the vessel may be tightly closed.

In addition to the usual handle *d* the vessel *a* is provided with a handle *d'*, which is formed similar to a bureau-handle.

What I claim is—

1. The combination of vessel *a* with a seat *b* and with clasps *b'* for securing the seat to the vessel, substantially as specified.

2. The combination of vessel *a* with a seat *b*, made of horseshoe shape, clasps *b'* for securing the seat to the vessel, and a cover *c*, 45 hinged to the seat and having a thickened end *c'*, substantially as specified.

ERNEST WENIGMANN.
